UNITED STATES PATENT OFFICE

FORRESTER L. HAMMER, OF BRANFORD, CONNECTICUT, ASSIGNOR TO MALLEABLE IRON FITTINGS COMPANY, OF BRANFORD, CONNECTICUT, A CORPORATION OF CONNECTICUT

DESIGN FOR A HOUSING FOR OIL BURNERS AND THE LIKE

Application filed February 24, 1932. Serial No. 42,973. Term of patent 14 years.

To all whom it may concern:

Be it known that I, FORRESTER L. HAMMER, a citizen of the United States, residing in Branford, in the county of New Haven and State of Connecticut, have invented a new, original, and ornamental Design for a Housing for Oil Burners and the like, of which the following is a specification, when taken in connection with the accompanying drawings, in which

Fig. 1 is a top plan view of an oil burner housing embodying my new design;

Fig. 2 is a side elevational view of the same.
I claim:

The ornamental design for a housing for oil burners and the like substantially as shown.

FORRESTER L. HAMMER.
